M. A. KLING

Des. 127,861

APRON

Filed July 3, 1940

FIG. 1.

FIG. 2.

INVENTOR:
MAXINE A. KLING.
By Martin P. Smith, ATTY.

UNITED STATES PATENT OFFICE

127,861

DESIGN FOR AN APRON

Maxine A. Kling, Hollywood, Calif.

Application July 3, 1940, Serial No. 93,403

Term of patent 3½ years

To all whom it may concern:

Be it known that I, Maxine A. Kling, a citizen of the United States, residing at Hollywood, in the county of Los Angeles and State of California, have invented a new, original, and ornamental Design for Aprons, of which the following is a specification, reference being had to the accompanying drawing, forming part thereof.

Fig. 1 is a front elevational view of an apron, showing my new design.

Fig. 2 is a rear elevational view of the apron shown in Fig. 1.

I claim:

The ornamental design for an apron, as shown.

MAXINE A. KLING.
